UNITED STATES PATENT OFFICE.

OSCAR W. NOBLE, OF LYNN, MASSACHUSETTS, ASSIGNOR TO HIMSELF AND
ROBERT L. MURKLAND, OF SAME PLACE.

GRATE FOR STOVES AND FURNACES.

SPECIFICATION forming part of Letters Patent No. 257,745, dated May 9, 1882.

Application filed March 22, 1882. (No model.)

To all whom it may concern:

Be it known that I, OSCAR W. NOBLE, a citizen of the United States, residing at Lynn, in the county of Essex and State of Massachusetts, have invented certain Improvements in Grates for Stoves and Furnaces, of which the following is a full, clear, and exact description, reference being had to the accompanying drawings, making part of this specification, in which—

10 Figure 1 is a plan of a stove-grate constructed in accordance with my invention. Fig. 2 is a vertical section through the center of the same on the line *x x* of Fig. 1. Fig. 3 is a vertical section on the line *y y* of Fig. 1. Fig. 4 is a perspective view of the central dumping portion of the grate; Fig. 5, a sectional detail.

15 My invention consists in the combination, with an open center grate, of a central dumping portion, of convex form on its upper side, so hung or pivoted to the grate itself that while being turned or dumped the distance between its convex surface and the edge of the central opening in the grate will always remain the same, thus preventing the coal or clinkers 20 from getting between the grate and the dumping portion on the side toward which the latter is turned and obstructing its movement, while the pivoting of the arbor of the dumping-center directly to the grate itself, instead of to 25 an adjacent portion of the stove-frame, as heretofore, enables the arbor to be used for the double purpose of shaking the grate horizontally and dumping the center, thus simplifying the construction and greatly facilitating 30 these operations; and my invention also consists in certain details of construction, as hereinafter set forth and specifically claimed.

In the said drawings, A represents that portion of the base or frame of the stove which 35 contains the circular grate B, which rests upon supports *a* projecting from the base, and is adapted to be shaken by reciprocating it in a horizontal plane. This grate B is provided with a series of downwardly-inclined and inwardly-projecting radial arms or bars, *b*, of 40 such length as to leave a large central opening, *c*, within which is fitted the central dumping portion, D, the upper surface of which is of convex form, as seen in Figs. 2, 3, and 4. 45 This portion D is so mounted on an arbor, E,

located below the plane of its lower edge, that when rotated it will have a crank motion, the inner portion of the arbor being pivoted in a lug, *d*, projecting down from the grate-bars *b*, while the outer portion has its bearings in a 55 bifurcated lug, G, also projecting from the grate, in which it is supported by a pin, *f*; and with this construction and arrangement the dumping portion D moves in the arc of a circle having its center at a point which will 60 cause the distance between its convex upper surface and the edge of the central opening, *c*, of the grate B, formed by the inner ends of the bars *b* on the side toward which the portion D is turned, to always remain the same 65 during the operation of dumping, which is an important feature, as it prevents coal or clinkers from getting between the grate and the portion D on the side toward which the latter is turned, and thus obstructing or clogging it, 70 as would be liable to occur if the width of the opening between them was at any time increased, while when the portion D is dumped the central opening, *c*, of the grate is left entirely clear and open to its full extent, which 75 is of great advantage, especially in removing clinkers. The central portion, D, is weighted to keep it in its proper position when up, as seen in Fig. 3, and the convex upper surface of this portion extends above the edge of the 80 opening *c* or the inner ends of the grate-bars *b*, the apex or highest part 6 being on a level with the outer edge of the grate B.

The arbor E is provided with a collar or flange, *g*, extending partially around it, the 85 ends 7 8 of the flange forming stops, which strike alternately against a projecting rib or portion, *h*, of the lug G, and thus limit the rotation of the dumping portion D in either direction, the flange *g*, by taking a bearing 90 against the inner surface of the lug G, also serving to hold the arbor E in place and prevent it from being withdrawn in the direction of its length.

The grate B is provided with the usual stops, 95 9 10, to limit its movement in either direction while being shaken, and by placing the lugs *d* G for supporting the dumping portion on the grate itself the entire grate, with the dumping portion, can be removed at a single operation, 100

thus avoiding the trouble and annoyance which have heretofore been experienced in grates of this description where the dumping portion is pivoted to the frame of the stove. It will be seen that the dumping can be effected at any time and when the grate is in any position, and by thus combining the shaking and dumping devices so that they can be operated by a single shaft or arbor, E, instead of having one

10 device for dumping and another for shaking, as has heretofore been customary in dumping center grates, the construction is greatly simplified and the cost materially reduced, while the grate is much less liable to become clogged 15 or be broken or deranged by hard usage.

I am aware that a grate has been constructed having a central opening provided with an independent dumping portion, and therefore make no broad claim to such device; but

20 What I claim as my invention, and desire to secure by Letters Patent, is—

1. The combination, with the open-center

grate B, of the convex central dumping portion, D, extending up above the edge of the central opening, e, and pivoted directly to the 25 grate B, said portion D being provided with a shaft or arbor, E, which serves the double purpose of reciprocating or shaking the grate and dumping the central portion thereof when the grate is in any position, substantially as described. 30

2. The combination, with the grate B, dumping portion D, and lug G, with its rib or portion h, of the arbor E, provided with a collar or flange, g, extending partially around it, and 35 having ends 78, which form stops for limiting the movement of the dumping portion D in either direction, substantially as described.

Witness my hand this 13th day of March,
A. D. 1882.

OSCAR W. NOBLE.

In presence of—

P. E. TESCHMACHER,
W. J. CAMBRIDGE.
